UNITED STATES PATENT OFFICE.

FRANK MAYCOMBER, OF SOUTH JACKSONVILLE, FLORIDA.

BATH-TUB ATTACHMENT.

1,212,659.

Specification of Letters Patent. Patented Jan. 16, 1917.

Application filed July 26, 1916. Serial No. 111,508.

To all whom it may concern:

Be it known that I, FRANK MAYCOMBER, a citizen of the United States, residing at South Jacksonville, in the county of Duval and State of Florida, have invented certain new and useful Improvements in Bath-Tub Attachments, of which the following is a specification, reference being had to the accompanying drawings.

10 This invention relates to bath tubs and has for its primary object to provide improved means for supplying water to the bath tub wherein the water is delivered into the tub in divergent streams over the bottom surface 15 thereof so that all sedimentary matter may be washed therefrom and removed.

It is an additional object of the invention to provide a vertically movable overflow pipe formed at its lower end with a valve 20 or closure for the drain or outlet pipe.

It is still another object of the invention to provide a water supply means for bath tubs; lavatories and the like, wherein the water is supplied to or drained from the 25 tub through the same opening or port.

It is a further general object of my invention to provide a plumbing fixture of the character stated which is simple and inexpensive in its construction, may be easily 30 adapted and applied to the ordinary bath tub and will materially add to the neat and attractive appearance of the same.

With the above and other objects in view, my invention consists in the novel features 35 of construction, combination and arrangement of parts to be hereinafter more fully described, claimed and illustrated in the accompanying drawing, in which—

Figure 1 is an end elevation of a bath tub 40 equipped with my improved water supply and drainage attachment; Fig. 2 is an irregular vertical sectional view; Fig. 3 is a section taken on the line 3—3 of Fig. 1; and Fig. 4 is an enlarged detailed fragmentary 45 section showing the means for lifting the overflow pipe.

Referring in detail to the drawing, 5 designates a bath tub which may be of any desired form and is preferably enameled in the 50 usual manner. Upon the exterior face of one of the end walls of the tub 5, preferably at the foot thereof, a central, vertically extending housing or boxing 6 is secured. The lower end or bottom wall of this boxing is 55 formed with a tapering, downwardly ex-

tending nipple 7 which is adapted to seat within the end of the drain pipe 8 which projects upwardly through the floor. The inner surface of this nipple constitutes a valve seat to receive the lower contracted 60 or tapering end 10 of a vertically movable overflow pipe 9 which is mounted within the boxing 6.

In the upper edge or marginal flange formed upon the end wall of the tub 5, a 65 plate 11 is countersunk and secured to said wall by means of suitable screws. This plate is formed with a rectangular opening, the edges of which are offset to provide a seat for a perforated plate or dish 12 adapted 70 to receive a cake of soap. The opening in the plate 11 coincides with an opening in the horizontal marginal wall on the tub which communicates with the interior of the boxing or housing 6. To the dish or 75 plate 12, a circularly arranged series of downwardly projecting rods 13 are fixed, and to the extremities of said rods, a ring or collar 14 is securely attached. As seen in Fig. 2 of the drawings, the rods 13 extend 80 downwardly into the upper end of the boxing 6 and the upper end of the overflow pipe 9 extends through the ring or collar 14 and is guided thereby in its vertical movement. The plate or dish 12 provides a convenient 85 receptacle or support for the cake of soap, and the water is drained therefrom through the perforations in the plate into the boxing 6.

To the pipe 9, below the collar 14, one 90 end of a chain 15 is connected, said chain extending upwardly and outwardly through an opening 16 formed in the wall of the housing 6. To the free end of said chain, a suitable handle member 17 is connected. 95 Thus, it will be understood that, by pulling the chain 15 upwardly and outwardly through the slot or opening 16, the pipe 9 may be raised. The lower end of the opening 16 is reduced in width to receive one of 100 the chain links, whereby the pipe may be held in its raised position. Normally, it will be understood that the tapering lower end 10 on the overflow pipe 9 is engaged upon the valve seat formed by the nipple 7 105 on the lower end of the boxing and securely closes said nipple.

The end wall of the tub 5, at its lower end, has a horizontal slot 19 formed therein substantially equal in length to the width of 110

the boxing 6, said slot affording communication between the boxing and the tub at the upper surface of the bottom wall of the tub. 20 and 21 designate the cold and hot water pipes respectively, which extend upwardly through the floor, exteriorly of the boxing 6 and on opposite sides thereof. These pipes extend inwardly into the boxing at the top thereof and then downwardly, as shown at 10 22 and 23 respectively, to the lower end of the boxing. These lower ends of the pipes 20 and 21 are laterally projected at an oblique angle and flared, as shown at 24 and 25 respectively, to form spray nozzles. The 15 open ends of these flared or flat spray nozzles are opposed to the opposite ends of the slot 19 in the end wall of the tub. Each of the pipes 20 and 21, where it enters the upper end of the boxing 6, is provided with a 20 cut-off valve 26 and 27 having a suitable operating rod 28 and 29 extending through the wall of the boxing 6.

It is to be particularly noted that when the pipe 9 is in its normal position, the upper end thereof is disposed some distance below the valves 26 and 27 so that the water will overflow into the upper end of said pipe before reaching said valves or the opening 16. Thus, the necessity of employing packing glands or other water-tight connections is avoided.

In the operation of the invention, when it is desired to clean the bottom of the tub, the chain 15 is pulled in the manner above 25 explained, to raise the overflow pipe 9 and disengage the lower end 10 thereof from the nipple 7. The valves 26 and 27 will now be opened and the water ejected from the angularly disposed nozzles 24 and 25 30 through the opposite ends of the slot or port 19. The water will thus be sprayed outwardly directly upon and over the bottom surface of the tub and toward the sides thereof to thoroughly clean the same and remove any sedimentary matter adhering 35 thereto. The water will then flow inwardly toward the center of the tub and outwardly through the central portion of the slot or port 19 and through the nipple 7 to the 40 drain pipe 8. In order to fill the tub, the pipe 9 is lowered so as to close the nipple 7 and the hot or cold water supply, or both, are turned on. The tub will gradually fill, as well as the boxing or housing 6, and all 45 splashing or noise is obviated, which is one of the disadvantages of the usual supply faucets mounted in the tub wall at the top thereof. When the water rises in the boxing 6 to the top thereof, the overflow will be 50 carried off by the pipe 9 to the drain 8. To empty the tub, the pipe 9 is lifted or moved upwardly in the manner above stated so that the water will quickly be drained off through the slot or port 19. By thus supplying 55 water to the tub and draining the same

through a single port or opening, it will be appreciated that the expense incident to the application of the supply fixtures to the tub is materially reduced, and considerable more room is afforded in the tub by the elimination of the projecting faucets on the end wall thereof. 70

A tub provided with my invention will also present a much neater and more attractive appearance. For the purposes of 75 illustration, I have disclosed the device in the accompanying drawing applied to a bath tub, but it is, of course, manifest that by resorting to obvious expedients and mechanical alterations within the knowledge of a 80 skilled plumber, the device can also be applied to lavatories and like toilet conveniences. It is also to be understood that while I have shown and described the preferred construction and arrangement of the 85 several parts, the same are nevertheless susceptible of considerable modification and I, therefore, reserve the privilege of adopting all such legitimate changes as may be fairly embodied within the spirit and scope of the 90 invention as claimed.

Having thus described this invention, what is claimed is:—

1. The combination with a bath tub having a common inlet and outlet opening in 95 one of its end walls at the lower end thereof, of a vertically disposed housing exteriorly fixed to said end wall, said opening communicating with the lower end of the housing, a drain pipe connection at the 100 lower end of said housing, a manually operable valve to close said drain pipe, and water supply pipes extending into the housing and provided with discharge nozzles to eject streams in divergent directions through the 105 opening in the wall of the tub.

2. The combination with a bath tub having a slot in one of its end walls at the upper surface of the bottom of the tub, of a vertically disposed housing exteriorly fixed 110 upon said end wall, a drain pipe connection at the lower end of said housing, said slot communicating with the interior of the housing, water supply pipes extending into the housing, said pipes being provided with 115 discharge nozzles opposed to the opposite ends of said slot to eject water into the tub, and a manually operable valve member to open or close the drain pipe connection.

3. The combination with a bath tub having a slot in one of its end walls at the upper surface of the bottom of the tub, of a vertically disposed housing exteriorly fixed upon said end wall, a drain pipe connection at the lower end of said housing, said slot 125 communicating with the interior of the housing, water supply pipes extending into the housing, said pipes being provided with discharge nozzles opposed to the opposite ends of said slot to eject water into the tub, 130

a vertically movable overflow pipe arranged within the housing, the lower end of said pipe normally closing communication between the drain pipe and the interior of the housing, guide means for said pipe, and manually operable means to lift the pipe and permit the water to drain from the tub through the slot in the wall thereof.

4. The combination with a bath tub having a slot in one of its end walls at the upper surface of the bottom of the tub, of a vertically disposed housing fixed to the exterior of said wall, said slot communicating with the lower end of the housing, a drain pipe connection secured to the lower end of the housing, hot and cold water supply pipes extending into the housing and provided with obliquely disposed nozzles to discharge water in divergent directions through the opposite ends of said slot, an overflow pipe vertically movable in the housing, the lower end of said pipe constituting a valve to normally close the drain pipe connection, guide means for said pipe, and manually operable means to raise the pipe and permit the water to drain through

the slot in the wall of the tub into the drain pipe.

5. The combination with a receptacle having a common inlet and outlet opening at the base thereof, of water supply means including pipes arranged to discharge water under pressure in divergent streams through said opening over the surface of the bottom wall of the receptacle and toward the opposite side walls thereof.

6. The combination with a receptacle having a common inlet and outlet opening, a drain pipe in communication therewith, and a valve to close said drain pipe, of water supply means including a pipe having a spray nozzle to discharge water under pressure through said opening in a horizontal direction immediately upon and over the surface of the bottom wall of the receptacle.

In testimony whereof I hereunto affix my signature in the presence of two witnesses.

FRANK MAYCOMBER.
